(57) **CLAIM**

The ornamental design for a dimmer-universal remote control illuminating system, as shown and described.

DESCRIPTION

FIG. 1 is a front elevational view of a dimmer-universal remote control illuminating system showing my new design; FIG. 2 is a rear elevational view thereof; FIG. 3 is a side elevational view thereof; FIG. 4 is a top plan view thereof; FIG. 5 is a bottom plan view thereof; and, FIG. 6 is a perspective view thereof.

The indicia shown in broken lines are for illustrative purposes only and form no part of the claimed design.
